(57) **CLAIM**

The ornamental design for a display panel with news headlines graphical user interface, as shown and described.

DESCRIPTION

FIG. 1 is a front view of a first image in a sequence of a display panel with news headlines graphical user interface. FIG. 2 is a front view of a second image in the sequence of a display panel with news headlines graphical user interface. FIG. 3 is a front view of a third image in a sequence of a display panel with news headlines graphical user interface; and,

FIG. 4 is a front view of a fourth image in the sequence of a display panel with news headlines graphical user interface. The appearance of the animated image sequentially transitions between the images shown in FIGS. 1-4, respectively. The process or period in which one image transitions to another forms no part of the claimed design.
